UNITED STATES PATENT OFFICE

WILLIAM C. SPIETH, OF GENEVA, OHIO

ELECTRIC-ARC LAMP

Application filed September 10, 1925. Serial No. 55,609.

This invention relates to electric-arc lamps, and particularly to lamps having a luminous or flaming arc, which lamps are especially adaptable for blue-printing, photo-engraving, 5 photo-lighting, and photo-chemical reactions.

The primary object of the present invention is to provide a lamp which will produce 10 a great volume of illumination of exceptional brilliance and actinic value.

Another object of the invention is the provision of a lamp that gives a maximum of illumination or lighting efficiency with a minimum amount of current consumed.

15 A further object of the invention is to provide an intensified arc giving a great volume of illumination with an economical operation, so that a highly efficient plant may be maintained at comparatively low cost.

20 Another object of the present invention is to provide an arc lamp construction that can be used as a complete lighting unit, and self-contained blue-printing equipment.

25 Among the novel features of the construction is the arrangement for automatic electrode adjustment, whereby the arc is maintained uniform with the production of a steady flame.

30 Other features are the arrangement and operation of the magnet coils, the construction and arrangement of the armature provided with an armature spring connection, and the provision of an air-pot and air-pot yoke construction for the insurance of a uniform, steady flame.

35 Further features are the top construction, providing for a three wire system between the lamp and rheostat, also a center tubular carbon holder and carbon cable.

40 Other important factors are the carbon clutch, the arrangement of a heat shield and other insulating elements.

45 The invention further provides a reflector so constructed and arranged that it is efficient and convenient for use in blue-printing and photography, providing ready access for lamp trimming, and allowing an air pocket back of the lamp and drafts in front, thereby cushioning both the front and back of 50 the lamp and intensifying the light.

The invention further provides a multiple unit resistance with a dial so constructed that provision is made for three wire system to give super-efficiency in addition to the two terminals provided for in the line service. 55 The rheostat is so constructed that it acts as a booster providing a direct ratio of increase in illumination as the square of the added amperes from its lowest to its highest point. This rheostat is adaptable to any amperage 60 either for direct or alternating current on either 110 or 220 volts service of enclosed or open arc lighting service.

This special construction, with its arrangement of elements and peculiar windings is 65 adaptable to all single arc lamps either of enclosed or open arc type, using the enclosed arc carbons of the cored, or solid type, or cored open arc white flaming carbons for blue-printing and other photo-chemical 70 processes.

The various features of novelty constituting the invention will be hereinafter especially pointed out in the claim, but for a full understanding of the invention in its various 75 aspects, reference is to be had to the following detailed description taken in connection with the accompanying drawings wherein—

Figure 1 is a front elevation of the improved lamp without the reflector and rheostat connections. 80

Fig. 2 is a side elevation of the bare lamp.

Fig. 3 is a front elevation of the lamp with the reflector and other accessories attached, but with a part of the reflector broken away. 85

Fig. 4 is a side elevation.

Fig. 5 is a top view of the reflector.

Fig. 6 is a diagrammatic view of the three wire system.

Referring to the drawings, 1 represents a 90 canopy to which is attached the hanger 2, and which supports the frame and operating elements of the lamp. A split tubular member 3 depends vertically from the center of the canopy 1 and has a housing 4 attached to its lower 95 terminal. Supported on said housing, and insulated therefrom, is a circular bracket 5 which forms a rest for the conductors 6^a and 6^b, said conductors being branches of the conductor 6 which is connected with the nega- 100

tive binding post 7. Arms 4^a on the housing 4 provide supports for frame rods 8, said rods being insulated from the housing, and provided with sleeves of ceramic or vitreous material. The upper terminals of the rods 8 are connected with the conductors 6^a and 6^b respectively, and the lower terminals are connected by a yoke 9 provided with a socket 9^a which supports the carbon electrode 10, said carbon being adjustably held therein by a set screw 11. The housing 4 also supports a horizontally disposed disk 12. Said disk is composed of heat resisting or opposing material, such as hard asbestos, or vitreous material, and acts to protect the upper parts of the lamp from the heat of the arc which is formed at A.

The upper movable electrode 13 is slidable in the tube 3 and has a clasp 14 clamped thereto, the clamp 14^a of said clasp extending through a vertical slot 3^a in the tube 3, and providing for the connection of the conductor 15. The conductor 15 is connected with the positive binding post 18 through an intermediate binding post 16 and a conductor 17.

A two spool solenoid 19, of heavy winding, is supported by the canopy 1 and is connected through the binding post 16 with the conductor 17, and through the binding post 20 and conductor 21 with the positive binding post 22. The cores of the solenoid are connected at their lower ends by a cross-bar thereby forming a U-shaped core frame 23. The frame 23 is mounted upon the upper member 30 of an elliptical spring 24, and the lower member of said spring is pivotally connected with a clutch-rod 25. The clutch-rod 25 passes through a fixed guide bracket 26, and is pivotally attached, at its lower end, to the carbon-clutch 27 disposed over the heat shield 12.

For the purpose of controlling the movement of the cores within the spools of the solenoid, and to insure a slow and steady movement when the solenoid is acting to separate the carbons, an air-pot 28 is provided, and a rod 29 is connected with the plunger of said air-pot and extends downward to a bearing on top of the carbon-clutch 27.

The current entering the lamp flows from the positive binding posts 18 and 22 to the binding post 16 one part directly through the conductor 17 and another part through the conductors 21 and 19^a and the solenoid 19, and then from the binding post 16 by conductor 15 to the upper carbon 13, thence to the lower carbon 10, thence by yoke 9, rods 8, and conductors 6^a and 6^b, through cable 6 to the negative binding-post 7.

For blue-printing and photography a reflector 30 is provided. Said reflector is formed as shown in Figs. 3, 4, and 5, and is attached to the lamp by means of flanged sleeves 30^a which clasp the insulating sleeves 8^a on the rods 8. The reflector extends forward from the supports 8^a, flaring outward to

an open front of large area, and is provided with apertures 30^b in the top and bottom in juxtaposition to the front. A semi-circular reflecting member 30^c is hinged to the member 80, as shown at 30^d, and extends back of the lamp, a fragmentary bottom 30^e providing an air-pocket back of the electrodes. This member 30^c being hinged to member 30 provides convenient access to the electrodes for trimming.

A cup 31 suspended from the yoke 9 provides a receptacle for carbon dust, scale, and other extraneous particles which may descend from the lamp.

Fig. 6 illustrates, diagrammatically, the hook-up of the three wire system in connection with the rheostat and special dial. In the present embodiment a ten-fold resistance 32 is connected with a dial 33 by conductors 34. Two positive terminals 36 and 37, and one negative terminal 35, are carried on the dial 33. A conductor *a* extends from the terminal 35 to the lamp connection 7 and through conductor 6 to the lamp frame or lower carbon support. The conductor *b* extends from the terminal 36 to the lamp connection 18, and through conductor 17 and binding post 16 and conductor 15^a to the upper carbon holder 3. Conductor *c* extending from terminal 37 to lamp connection 22 is connected with the upper carbon holder 3 through conductor 21 and the solenoid 19 and conductor 19^a and binding post 16 and conductor 15^a. Lines *b* and *c* are shunted to the resistance 32 by conductors 38 and 39. The amount of resistance is governed by the rotary switch 40 acting on the contact plates 41.

This connection of the two positives *b* and *c* with the resistance 32 acts as a booster providing a direct ratio of increase in illumination as the square of the added amperes from its lowest to highest point, 14 to 50 amperes on 110 volts and 7½ to 25 amperes on 220 volts.

From the above description it will be apparent to those skilled in the art that on the initial points of the rheostat the arc is in series with the solenoid, and the solenoid regulates the gap in response to the current flow, in the usual manner, and that that part of the current always does flow to the lamp through the solenoid, but that the additional current flowing upon the advance of the rheostat arm to cover additional points flows through the conductors 6 and 18 directly to the binding post 16 and upper carbon holder 3 without passing through the solenoid 19, and it will therefore be understood that this additional current does not operate to lengthen the arc gap, so that, by movement of the rheostat beyond the initial points, I may pass additional current through the arc without change in the length of the gap, to thus greatly increase the

power of the gap, and the illumination from the arc.

What I claim and desire to secure by Letters Patent is:

5 A reflector, for use with an arc lamp of a type having vertically extending members flanking the arc on the two sides of the arc, serving as conductors to the lower electrode, and surrounded by insulating sleeves, comprising a top, a base, and a lateral wall connecting said top and said base, and provided with means adapted to clamp said sleeves to hold said reflector supported on said lamp.

10 In testimony whereof I affix my signature,
15 WILLIAM C. SPIETH.
